FLEXIBLE PACKAGE FOR FLUENT SUBSTANCES

Joseph L. Arcudi, Elizabeth, N.J., assignor to Ivers-Lee
Company, Newark, N.J., a corporation of Delaware

Filed Mar. 21, 1966, Ser. No. 1,568

Term of patent 14 years

(Cl. D58—2)

FIGURE 1 is a front elevation of a flexible package for fluent substances showing my new design, the rear elevation being a mirror image thereof;

FIGURES 6, 7, 8, 9, 10 and 11 are horizontal sectional views on the planes of the respective lines 6-6, 7-7, 8-8, 9-9, 10-10 and 11-11 of FIGURE 1.

I claim:

The ornamental design for a flexible package for fluent substances, as shown and described.
